UNITED STATES PATENT OFFICE

163,835

STORE FRONT

Samuel C. Wagenman, Cleveland, Ohio

Application December 22, 1950, Serial No. 13,537

Term of patent 14 years

(Cl. D13—1)

To all whom it may concern:

Be it known that I, Samuel C. Wagenman, a citizen of the United States, residing at Cleveland, county of Cuyahoga, and State of Ohio, have invented a new, original, and ornamental Design for a Store Front, of which the following is a specification, reference being had to the accompanying drawing, forming part hereof.

Fig. 1 is a perspective view of a store front, showing my new design;

Fig. 2 is a front elevational view of the same, and

Fig. 3 is a plan view of the store front on a reduced scale.

The essential features of the design are shown in full lines, and the side of the store front opposite that shown in Fig. 1 is substantially the same as the one disclosed.

I claim:

The ornamental design for a store front, substantially as shown and described.

SAMUEL C. WAGENMAN.
